SNOW PLOW BLADE

Robert Maurice Hilton, 28055 Ridge Road,
Damascus, Md.

Filed Feb. 19, 1965, Ser. No. 83,892

Term of patent 14 years

(Cl. D35—2)

FIG. 1.

FIG. 2.

FIG. 3.

FIG. 6.

FIG. 4.

FIG. 5.

FIGURE 1 is a three-quarter frontal perspective view of the snow plow blade, showing my new design, wherein the broken line shown representing a propelling vehicle is for illustrative purposes only;

FIGURE 2 is a front elevational view of the plow blade of FIG. 1, with said vehicle again shown for illustrative purposes only in dotted outline;

FIGURE 3 is a rear elevational perspective view of the plow blade of FIGS. 1 and 2, shown on an enlarged scale;

FIGURE 4 is an enlarged top plan view of the blade of FIGS. 1-3;

FIGURE 5 is a bottom plan view thereof; and

FIGURE 6 is a side elevational view of the side opposite that shown in the perspective view of FIG. 1.

The dominant features of my design reside in those portions shown in full lines.

I claim:

The ornamental design for a snow plow blade, substantially as shown and described.
